V. J. DE YOUNG

2,578,879

ADJUSTABLE BISECTIONAL BACK REST

Filed Sept. 15, 1945

UNITED STATES PATENT OFFICE

2,578,879

ADJUSTABLE BISECTIONAL BACK REST

Verne Jack De Young, Spring Lake, Mich., assignor to Sturgis Posture Chair Company, Sturgis, Mich., a corporation of Michigan

Application September 15, 1945, Serial No. 616,588

4 Claims. (Cl. 155—158)

1

The main objects of this invention are:

First, to provide a posture chair in which the back is adjustable to the individual using the chair comprising a pair of back members which are adjustable horizontally and these back members being supported for vertical adjustment as a unit and from front to rear relative to the seat.

Second, to provide a posture chair which supports the body of the user of the chair in a manner well adapted to relieve strains and minimize fatigue.

Third, to provide a structure having these advantages which is simple and economical in its parts and easily adjusted for particular requirements.

Objects relating to details and economies of the invention will appear from the description to follow. The invention is defined and pointed out in the claims.

A preferred embodiment of the invention is illustrated in the accompanying drawing, in which:

Fig. 1 is a side elevation of a chair embodying my invention, a figure being conventionally illustrated thereon.

Fig. 2 is a fragmentary front elevation.

Fig. 3 is a fragmentary plan view.

Fig. 4 is an enlarged detail section on line 4—4 of Fig. 3 showing details of the mounting of the back members.

Fig. 5 is an enlarged fragmentary view in section on line 5—5 of Fig. 1.

The embodiment of my invention illustrated comprises a pedestal designated generally by the numeral 1, the chair seat 2 being supported by the swivel supporting spindle 3. This spindle is adapted for vertical adjustment but as that forms no part of my present invention it is not described herein.

The spindle is provided with a rearwardly projecting bracket 4 to which the rearwardly curved back bar 5 is connected by means of the arm 6. The arm 6 is adjustably connected to the bracket at 7 while the back bar is adjustably connected to the arm 6 at 8. This adjustment comprises a clamping head 9 on the arm 6 and a coacting clamp member 10 with clamping screw 11. The connection for the arm to the bracket is desirably the same as that illustrated in Fig. 5 and therefore is not detailed.

The adjustable arm 6 and the adjustable connection for the back bar 5 to the arm 6 permits the vertical adjustment of the back bar and also tilting adjustment of the back bar—

2

that is, adjustment of the back bar forwardly and rearwardly relative to the seat.

The back bar is provided with forwardly inclined cross arms 12 at its upper end and padded back members 13 are mounted on these arms for longitudinal adjustment thereon and also for tilting adjustment, this being accomplished by the clamps 14 embracing the cross arms 12, the clamp being split and provided with clamping screws 15, see Fig. 4.

By this arrangement of parts the back members can be adjusted to properly fit the body of the user and to engage the user's back at a point most comfortable to the user both vertically and also to conform to the particular user.

The adjustment of the back members to and from each other is designed to accommodate persons of different size as well as different body shapes. The tilting also enters into this.

I have illustrated and described a highly practical embodiment of my invention. I have not attempted to illustrate or describe certain other embodiments and adaptations as it is believed that this disclosure will enable those skilled in the art to embody and adapt my invention as may be desired.

Having thus described my invention, what I claim as new and desire to secure by Letters Patent is:

1. In a posture chair, the combination with a non-tiltable seat provided with a swiveled supporting spindle, of a back supporting bracket projecting rearwardly from said spindle below said seat, a rearwardly curved back bar, a supporting arm for said back bar adjustably connected to the lower end thereof and adjustably connected to said bracket whereby the back bar is supported for vertical and for front to rear adjustment, said back bar having a pair of laterally projecting cross arms at its upper end, a pair of padded back engaging members mounted on said arms for adjustment longitudinally thereof and for tilting adjustment thereon, said arms being inclined forwardly to conform approximately to the horizontal curvature of the back at the waist line, said arms constituting guideways for adjusting the back engaging members forwardly as the same are adjusted outwardly on said arms, and means for adjustably securing the back engaging members to the arms.

2. In a posture chair, the combination with a seat, of a back bar having opposed laterally projecting cross arms at its upper end, individual back engaging members mounted on said arms

for independent adjustment longitudinally thereof and for independent tilting adjustment thereon, said arms being inclined forwardly to conform approximately to the horizontal curvature of the back at the waist line, said arms constituting guideways for adjusting the back engaging members forwardly as the same are adjusted outwardly on said arms, and means for adjustably securing the back engaging members to the arms.

3. In a posture chair, the combination with a seat, of a back bar having opposed laterally projecting forwardly inclined cross guideways at its upper end, back engaging members supported by said guideways for adjustment longitudinally thereof and for vertical tiltable adjustment relative thereto, said guideways guiding the back engaging members forwardly as the same are adjusted outwardly thereof, the longitudinal line of adjustment of the back engaging members relative to the guideways corresponding approximately to the horizontal line of curvature of the back at the waist line, and means for holding the back engaging members in their positions of adjustment relative to the guideways.

4. In a posture chair, the combination with a seat, of a chair back having laterally projecting cross arms, back engaging members each having

10
15

5

a single pivotal connection on said arms for horizontal and tilting adjustment thereon, said arms being inclined forwardly to conform approximately to the horizontal curvature of the back at the waist line, said arms constituting guideways for adjusting the back engaging members forwardly as the same are adjusted outwardly on said arms, and means for adjustably securing the back engaging members to the arms.
